VENDING MACHINE

George P. Mergens, Manitowoc, Wis., assignor, by
mesne assignments, to U-Need-A-Merchan-
diser, Inc., Brooklyn, N. Y., a corporation of
New York

Application February 26, 1938, Serial No. 192,724

6 Claims. (Cl. 312—94)

My invention relates to improvements in means for vending or dispensing various articles, packages or other merchandise, and the same has for its object to provide a simple, efficient and reliable apparatus which may be operated, in the presence of the proper coin or token, to cause the discharge or release of the article or package.

Further, said invention has for its object to provide an apparatus of the character specified in which the magazine or magazines thereof for receiving the articles or packages to be dispensed are provided with means capable of being successively actuated for individually supporting the articles or packages so that the weight of the upper packages or articles is not imposed upon the lower ones as in the case of the use of an ordinary stack.

Further, said invention has for its object to provide an apparatus of the character specified in which the magazines thereof each contains a series of vertically spaced shelves or supports capable of being successively actuated or released beginning with the lowermost one for discharging or dispensing the articles or packages supported thereon.

Further, said invention has for its object to provide an apparatus of the character specified in which the vertically spaced article supporting members thereof may be successively actuated or released by repeated movements of a suitable actuating means.

Further, said invention has for its object to provide an apparatus of the character specified in which the controlling or actuating means thereof is rendered inoperative after the last or uppermost article or package in any magazine is dispensed.

Further, said invention has for its object to provide an apparatus of the character specified in which means are included for releasing and causing the return to its initial position of the travelling member employed for successively releasing the article supporting members.

Further, said invention has for its object to provide an apparatus of the character specified in which the article supporting members are individually retained in operative position by a succession of latches disposed in the path of said traveller to be released thereby and automatically returned to position for locking said supporting members when the latter are returned to article supporting position.

Further, said invention has for its object to provide an apparatus of the character specified in which said traveller includes latch actuating

means adapted to ride over the latches in the locked position thereof upon the return of the traveller to its lowermost position.

Further, said invention has for its object to provide an apparatus of the character specified in which means is associated with said traveller operable in any position of the latter for causing the disengagement of the traveller pawls from their ratchets in releasing said traveller for returning the same to its lowermost position.

Further, said invention has for its object to provide an apparatus of the character specified in which the latch engaging means on said traveller is also under control of means carried by said traveller for retaining said means in latch actuating position and for releasing said means for movement over said latches in the return of the traveller to initial position.

Further, said invention has for its object to provide an apparatus of the character specified in which said traveller rides upon a rotatable shaft capable of being actuated for operating the several control means carried by the traveller.

Other objects will in part be obvious and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawings:

Fig. 1 is a front elevation of one form of apparatus constructed according to my said invention;

Fig. 2 is a rear elevation thereof with parts broken away and certain of the repeated parts omitted;

Fig. 3 is an enlarged detail plan view illustrating the traveller resetting means;

Fig. 4 is an enlarged detail section taken on the line 4—4 of Figs. 1 and 2 looking in the direction of the arrows;

Fig. 10 is a similar view showing the pawls in disengaged position;

Fig. 11 is an enlarged view of the traveller looking at the opposite side thereof;

Fig. 12 is a vertical section on the line 12-12 of Fig. 9 looking in the direction of the arrows; and

Fig. 13 is an enlarged horizontal section on the line 13-13 of Fig. 7 looking in the direction 10 of the arrows.

Referring to the drawings, the vending machine embodying my invention comprises the usual casing 10 which encloses the operating mechanism for preventing access thereto and 15 to the packages or articles contained therein. A back plate or supporting member 11 is disposed within the casing 10 for supporting a plurality of forwardly extending vertical partitions 12 at the front thereof forming the compartments or 20 magazines 13 therebetween, said partitions 12 having flanges 14 at the rear thereof securing the same rigidly to the back plate 11 and having relatively narrow flanges 15 at the forward edges thereof.

Each of the magazines 13 contains the article supporting members, such as the plates or shelves 16, arranged one above the other in spaced apart horizontal relation for supporting articles or packages and pivotally mounted at corresponding 30 sides thereof upon the partitions 12, as indicated at 17. As one example, the pivoted members 16 are preferably made of sheet metal and have pivot rods 18 secured thereto, such as by folding the material of said members of the corresponding 35 sides about said rods, as indicated at 19. Said rods 18 are relatively flat and project at the ends thereof beyond the members 16 to form pintles 20 and 21 pivotally supported respectively in the circular holes 22 in the front flanges 15 and 40 in the rear flanges 14 and back plate 11.

The supporting members 16 of each vertical series or row are normally retained in horizontal position by latching or locking means, indicated generally at 23, at the rear of the back plate 11, and preferably comprising a vertical series or row of latches or detents 24 each co-operating with a corresponding article supporting member 16 to 45 lock the same in position. The pintles 21 terminate in an angularly related finger 25 extending substantially vertically in the horizontal position of the shelf 16. Each latch 24 is pivoted at 26 intermediate its length to a finger 25. A right angular notch 27 is formed in the upper edge of the latch 24 towards the end thereof in the direction of the free side of the member 16. The notch 27 is adapted to engage and receive the lower edge portion of a lug or catch 28 projecting from the back plate 11. The latch 24 is normally retained 50 engaged with the lug 28 by a coil spring 29 secured at one end to the opposite end of the detent 24 and at its other end to the finger 25 at a point below the pivot 26 substantially in line with the pivotal axis of the member 16. The detent 24 is 55 also provided at its upper edge with an inclined cam portion 30 merging with the notch 27 and serving to guide the notch 27 into engagement with the lug 28 when the member 16 is returned to its horizontal or article supporting position. In the locking position of the latch 24 the spring 29 is tensioned and serves to effectively retain the latch in engagement with the lug or catch 28. When the latch is actuated to release or operate 60 the supporting member 16, the catch 28 is disengaged,

the weight of the supporting member together with that of the article thereon swings the latch to its downwardly inclined position, the tension of the spring 29 then becoming relieved 5 because of the change in angular relation between the finger 25 and latch 24. When the supporting member is returned to horizontal or operative position by hand, the spring 29 gradually tensions and the cam portion 30 guides the latch 10 24 into locking engagement with the catch 28 to retain the support 16 in position.

The detents 24 of each vertical row or series are successively actuated by mechanism 31 including a traveller 32 adapted to be fed or advanced step-by-step by said mechanism and having a finger 33 at the inner side thereof adapted to engage and trip the successive latches 24 to release the supports 16. The traveller 32 is 15 slideable mounted upon the vertical guide rods 34 and 35 serving in part as pawl and ratchet mechanism for advancing the traveller and preventing the return thereof during the dispensing operations. The rods 34 and 35 extend above and below the latches 24 and are supported at the upper portions thereof by a bracket 36 secured to the back plate 11 and at points below the latches 24 by the bracket 37 secured to the back plate 11 and also serving as a transverse support for the several travellers 32 in the lowermost positions 30 thereof. The rods 34 and 35 at the lower ends thereof below the bracket 37 are supported in the vertically spaced, transverse brackets 38 and 39 for movement therein as hereinafter described. 35 The rods 34 and 35 are provided with notches or teeth 40 and 41 respectively disposed longitudinally thereof in spaced apart relation, the teeth on the two rods being arranged in opposing pairs corresponding in number with the number of 40 latches 24 employed. In the normal position of the rods 34 and 35, the corresponding teeth 40 and 41 face each other, each tooth 41 however being offset downwardly slightly relative to its corresponding tooth 40. The teeth 40 and 41 co- 45 operate with a pair of pawls 42 and 43 pivoted upon the traveller 32 on the inner side thereof at 42' and 43' respectively between the rods 34 and 35 and normally retained in engagement with the guide rods by means of the interposed spring 44. The pawls 42 and 43 extend downwardly from their pivots into position to engage the respective notches or teeth 40 and 41 which are shaped or directed to insure the advance of the traveller 32 in an upward direction and to prevent downward or retrograde movement thereof.

The traveller 32 is advanced by the reciprocation of the ratchet or guide rod 34 in its bearings. 50 As one example of actuating means 45 for the several feed mechanisms 31, I employ a plurality of horizontally disposed rearwardly extending actuating shafts 46 rotatably mounted at the front in the lower front panel 47 of the apparatus 65 and at the rear in the back plate 11. The shafts 46 preferably project at the front thereof through the front wall 48 of the casing 10 and have the actuating knobs or handles 49 constituting the several selector elements accessible 70 at the front. The shafts 46 project rearwardly beyond the back plate 11, and between the guide rods 34 and 35. Each guide rod 34 is reciprocated by the operation of the corresponding shaft 46 through reciprocation of a relatively short 75

member or plunger 50 slidably mounted in the brackets 38 and 39 contiguous to and in parallelism with the rod 34 and provided at its upper end with a head 51 having an opening 52 therein through which the rod 34 passes. The rod 34 is reciprocated concomitantly with the plunger 50 by connecting said rod 34 to the head 51 for movement therewith by suitable means such as the cotter pins or the like 52a secured to the rod 34 at opposite sides of the head 51, the connection allowing rotation of the rod 34 in the head 51. A crank arm 53 secured to the rear end of the actuating shaft 46 causes the reciprocation of the plunger 50 through a link 54 pivotally connected at the ends thereof to the crank 53 and the lower end of the plunger 50. The return movement of the actuating means 45 is effected by the springs 45a secured at contiguous ends to the crank arm 53 and anchored 20 at the outer ends thereof at fixed points.

In vending machines embodying my said invention and employing two or more magazines 13 and a corresponding number of selective actuating means 45, I preferably provide means associated with the several selector means 45 for preventing actuation of more than one thereof at a time, such as the means indicated at 55 (Fig. 1). The means 55 may also serve as an actuator for any known coin controlled locking mechanism, 30 which since it forms no part of the present invention need not here be described in detail. The means 55 includes a transverse guide-way 57 slidably supporting a back member or slide 58 of a length substantially co-extensive with the width 35 of the apparatus and the elements 59 and 59a at the front of the slide 58 normally retained in end-to-end engagement with each other by a spring 60 secured to the right hand element 59a and to a fixed part of the frame. The left hand element 59 in the normal position shown bears 40 against a stop 61 secured to the slide 58 and movable therewith. The right hand element 59a is provided with a recess 62 in the upper edge thereof providing clearance for the member 63 which is secured to the slide 58 and serves as a 45 stop for retaining the elements 59 and 59a in position for a limited movement relative to slide 58. Said elements 59 and 59a are capable of such movement through a distance determined by the 50 spacing between the edge 64 of the slotted element 59a and the edge 64 of stop 63 respectively. The other edge 65 of the element 59a engages the opposite end of the stop 63 so that the slide 58 is returned to normal position by the action 55 of spring 60. The juncture edges between the stop 61, and elements 59, 59a are preferably beveled at the lower portions thereof to form recesses 66 adapted to receive the rollers 67 carried by the outer ends of the arms or fingers 68 secured to the shafts 46 and normally aligned with said recesses 66.

When it is desired to actuate the dispensing mechanism after the insertion of a proper coin into the apparatus and delivery thereof through chute 69 to the coin mechanism, the selected element 49 is rotated clockwise to cause the roller 67 to enter the adjacent recess 66 and move the elements 59—59a in advance thereof until the edges 64 and 64a engage each other. As such 70 position is attained the several elements 59—59a become wedged by the roller 67 to prevent relative movement between the parts, and hence preclude actuation of the remaining or other selector elements 45. However, as the clockwise movement 75 of the arm 68 is continued, the pressure

against the stop 63 secured to the slide 58 causes the latter to move transversely of the apparatus together with the elements 59, 59a without releasing said elements. The continued movement may serve to suitably actuate the coin controlled mechanism selected for association with my invention, in the presence of the proper coin therein, for unlocking the same to allow the dispensing operation. Upon the inauguration of the unlocking operation the full-stroke device 70 associated with each shaft 46 becomes operative to prevent return movement of the shaft 46 before the clockwise movement is completed.

The coin controlled mechanism is actuated by the straight line movement of the slide 58. For 15 this purpose the stop 63 has an extension 71 thereon associated with the mechanism 56. A locking detent 72 is pivoted at one end 73 to the extension 71 and extends through a slot 74 in the body 75 of the mechanism 56 towards the stop 16 20 25 and normally in the path of said stop to prevent operation of the apparatus in the absence of the proper coin. The detent 72 is retained within the slot by a spring 77. In the presence of the proper coin, actuation of the extension 71 causes 30 the detent 72 to be cammed outwardly by the coin to clear the stop 16. During this movement the coin rests upon a gate or support 78 covering the outlet for discharging the coin. After the unlocking operation a finger 79 movable with the extension 71 actuates the gate 78 to discharge the coin into a proper receptacle. When the clockwise movement of the actuating shaft 46 is completed as above described, the full-stroke device 10 35 40 45 50 55 60 65 70 75 70 becomes inoperative, allowing rotation of the shaft 46 in the opposite direction for then causing the release of the proper supporting member 16 as hereinafter described.

A coin controlled locking mechanism and locking means for preventing operation of more than one of the selector elements 49 at a time and for actuating a locking mechanism, which may be operatively associated with my invention concerned herein, is illustrated in application Serial No. 192,725, filed by me February 26, 1938.

In operation, the proper coin is inserted and the selector knob 49 is rotated clockwise to actuate the coin controlled mechanism 56 as above described to unlock the apparatus. The resulting movement of the shaft 46 actuates the plunger 50 50 to move the guide rod 34 downwardly through the traveller 32 when in its lowermost position. Upon completion of the unlocking operation rotation of the shaft 46 in the opposite direction moves the actuating rod 34 upwardly and causes the lowermost tooth 40 of the rod to engage the detent or pawl 42 carried by the traveller 32 to advance the latter one step for actuating the lowermost supporting member 16. The article or package carried by said member drops through 60 the open lower end 80 of the magazine 13 onto the chute 81 for delivery through the opening 82 in the front of the casing 10. Upon succeeding operations of the same actuator 49, the rod 34 is reciprocated in like manner to advance the traveller 32 step-by-step for successively releasing the detents 24 and dispensing the articles or packages. Upon each downward movement of the rod 34, the traveller 32 is held against retrograde or return movement in the successive advanced 70 position thereof by engagement of the pawl 43 carried thereby with the successive teeth 41 upon the rod 35.

When the traveller 32 attains its uppermost 75 position and the uppermost supporting member 75

16 is released, I preclude further operation of the rod 34 by means of a stop 83 secured to the rod 34 contiguous to the under side of the bracket 36 and adapted to engage the traveller 32 held in the uppermost position thereof against downward movement by its engagement with the rod 35. The stop 83 by engagement with the traveller 32 prevents operation of the selector element 49 controlling the exhausted magazine.

17 I also provide means 84 for simultaneously releasing the several travellers 32 in any of the successive positions thereof and allowing the same to return to their lowermost positions at rest upon the ledge 37. For this purpose actuating arms 85 are secured to the several rods 34 and 35 at the top of the ledge 36, said arms being disposed in parallelism and projecting forwardly and laterally. A transversely extending actuating member 86 is pivotally connected at 87 to the outer ends 20 of the several arms 85 and is normally retained in one position by a coil spring 88 secured at one end to the actuator 86 and at its opposite end to a fixed part. The member 86 has a finger piece 89 at one end thereof adapted to be grasped to 25 actuate the member 86 and simultaneously rotate the several rods 34 and 35 in their bearings. The several arms 85 are preferably retained in position by a transverse strap or member 90 disposed above the arms and secured at the ends thereof 30 to the ledge 36, said member having openings 91 therein through which the upper ends of the rods 34 and 35 project. In order to allow the detents 42 and 43 upon the travellers 32 to clear the rods 34 and 35 upon the rotation thereof, the latter 35 longitudinally thereof are provided with flats 92 and 93 in offset relation to the teeth 40 and 41 thereon, the flats 92 and 93 being disposed upon opposite sides of the corresponding rods as shown in Fig. 3 so that upon actuation of the member 86 40 the flats 92 and 93 of each pair of rods 34 and 35 will assume positions facing each other to enlarge the spacings between the rods allowing the travellers 32 to drop.

45 After the travellers 32 have been released the several supporting members or shelves 16 may be readily lifted by hand into their horizontal position, the detents 24 operating automatically to lock the shelves in position. The magazines 13 are accessible through the usual door in the casing 10 at the front for filling.

50 In Figs 7 to 13 the invention is shown including a modified form of traveller 32a for successively actuating the series 23 of latches 24 pivotally mounted upon the fingers 25 on the pivots 18 of the supports 16 for releasably locking the shelves 16 in article supporting position, said latching or locking means being similar in construction and operation to that shown in Figs. 1 to 6.

55 In the modification shown, a member 94, preferably in the form of a channel, is secured to the back plate 11 in vertically extending position to provide means 28a co-operating with said latches 24 to be engaged thereby for locking the shelves 16 in position and to provide ratchet means 35a 60 co-operating with said traveller 32a for preventing retrograde movement of the traveller.

65 The channel 94 is secured at a lateral flange 95 by suitable attaching means 96 to the back plate 11 in position with the channel thereof receiving the notched arms of the latches 24, the intermediate wall 97 of said channel having spaced openings 98 therein through which the latches project. The edge portions 99 at the top of the several openings 98 constitute the co-operating latching or catching means 28a to be engaged by

70 the notches 27 of the several latches 24 for locking the shelves 16 in article supporting position as above described. The remaining lateral flange 100 of the member 94 at the edge thereof is provided with spaced teeth 41a constituting the 5 ratchet means 35a. A transversely extending supporting member 101, preferably in the form of an angle, is secured by one flange thereof to the outer faces of the several members 94 at the lower ends thereof.

75 The traveller 32a is advanced by the vertically reciprocating ratchet member 34a beyond the opposite ends of the latches 24, preferably in the form of an angle provided with longitudinal slots 102 in the flange 103 thereof. The member 34a 15 is supported in position for reciprocation by means of a bolt or other guiding member 104 secured to the support 101 and riding in the lower slot 102 and by means of a similar device 105 secured to the back wall 11 and riding in the upper slot 102. The edge of the flange 103 is provided with spaced teeth 40a for co-operation with the traveller 32a. The member 34a is retained in elevated position with the devices 104 and 105 at the lower ends of the slots 102 by means of the 25 coil spring 106 secured at one end to the member and at the opposite end to the top plate 107. The member 34a is reciprocated by rotation of the selector shaft 46 in the manner described in connection with the disclosure of Figs. 1 to 6, said 30 shaft having a crank arm 53 connected through link 54 directly to the lower end of the reciprocating member 34a for actuating the traveller 32a.

35 The traveller 32a comprises a three-part body 108 adapted to ride upon and bridge the spaced flanges 100 and 103 of the ratchet members 35a and 34a respectively. The body 108 comprises a plate member 109 engaging the outer side of said flanges 100 and 103 and having a rearwardly directed supporting flange 110 at the upper end thereof provided with a bearing opening 111, a plate member 112 engaging the inner faces of said flanges 100 and 103, and an intermediate plate or block 113 of reduced width riding in the space provided between the opposing edges of 45 said flanges. The parts 109, 112 and 113 are secured together by means of the pins or screws 114 passing therethrough and serving as pivotal supports for the vertically extending juxtaposed pawls 42a and 43a co-operating with the ratchet 50 teeth 40a and 41a. The body 108 as thus formed provides grooves 115 at the vertical edges thereof receiving the toothed edges of the flanges 100 and 103.

55 The pawls 42a and 43a are pivotally supported towards the upper ends thereof by said pivot pins 114 upon the rear plate 109 and terminate at the lower ends in inwardly directed feet portions 116 adapted to engage the teeth 40a and 41a, and at the upper ends thereof in rearwardly directed 60 flange portions 117 in spaced relation to each other.

65 The teeth engaging portions 116 are normally maintained in engagement with the edges of said flanges 100 and 103 in cooperative relation with the teeth thereon by means of a spring 118 anchored at an intermediate point thereof to the post 119 upon the plate 112 and having legs 120 engaged at the ends thereof with said portions 116 to maintain the same in separated relation. 70

75 When the traveller 32a is advanced the successive latches 24 are actuated by the tripper or dog 121 supported by the plate 112 at the side thereof contiguous to the member 103 and having a nose 122 at its upper end normally dis-

posed for travel in the path including said latches.

Said dog 121 preferably comprises a vertically extending member pivotally supported at an intermediate point 123 thereof upon an ear 124 on the plate 112 so as to permit of said dog 121 freely riding over said latches in the shelf locking positions thereof upon the resetting or return movement of said traveller 32a as hereinafter described.

10 The member 121 during the latch operating advance of the traveller 32a is releasably held with the nose 122 projected into said path for actuating the latches 24 by engagement of a rotatable cam member 125 upon the traveller with the rearwardly directed arm portion 126 at the upper end of the member 121. The portion 127 of said member 121 below the pivot 123 is tapered to provide clearance so as to permit of the movement of the nose 122 into and from projected position relative to the contiguous face of the traveller 32a, the lower inner edge portion 128 of the member 121 in the projected position of the nose 122 firmly engaging the adjacent face of the traveller and co-operating with said cam 125 to hold the pivoted member 121 rigidly in position during the latch actuating operations thereof. By provision of a dog 121 capable of being released for free pivotal movement, I am able to effect the return of the traveller 32a to its lowermost position not only before the supporting members or shelves are returned to locked position, as required by the construction shown in Figs. 1 to 6 in which the latch actuator 33 is fixed, but also subsequent to said return, said pivoted dog 121 in the latter case being free to ride over the successive latches 24 in the locked positions thereof upon the return of the traveller.

In the form of the invention disclosed in Figs. 7 to 13 the ratchet members 34a and 35a are fixed during the operation of resetting the traveller 32a. The release of the pawls 42a and 43a from engagement with said ratchet members for releasing the traveller 32a is effected independently of said members by means of a rotatable cam member 129 disposed below the flange portion 110 between the opposing portions 111 at the upper ends of the pawls and having a bearing in the hole 111, said cam members 125 and 129 being preferably connected together and supported for joint rotation at opposite sides of the flange 110. The cams 125 and 129 are actuated by means of a rotatable member or shaft 130 having bearings at the ends thereof in the cross members 101 and 107 at the bottom and top of the structure and passing through an axial opening 131 through said cam structure 125-129 and keyed thereto for rotating the cams while allowing sliding movement of the traveller 32a along the shaft 130, the shaft 130 and 131 preferably being of corresponding polygonal cross-section. An arm 132 is secured to the upper end of the shaft 130, similar to the arms 85 of the traveller releasing means shown in Figs. 1 to 3, for actuating the shaft 130, either individually, or, if desired, simultaneously by a control similar to that shown in said Figs. 1 to 3, for effecting the release and return of the traveller 32a. The parts may be retained in either latch actuating position or in traveller releasing position, as shown in Fig. 10, by frictional engagement of the parts with each other, or a return spring 133 may be employed connected to the arm 132 for positively effecting the return of the parts to latch operating position upon the

manual release of the actuator 132 after the traveller has returned to its lowermost position.

When the parts are in the latch operating position shown in certain of the views, the cam 125 is positioned with its longer dimension directed to maintain the nose 122 in its projected position for successively actuating the latch 24, and the cam 129 is positioned between the portions 117 with its shorter dimension disposed transversely to allow the lower ends 116 of the pawls to engage the ratchets 34a, 35a under the action of the spring 118. The operation in which the traveller 32a is advanced step-by-step to trip the latches 24 is substantially the same as that described for the structure of Figs. 1 to 6. When the traveller 32a actuates the uppermost latch, the pin 83 on the member 34a engages the traveller to prevent actuation of the corresponding reciprocating member 34a when the magazine is empty. Utilizing the modified and preferred construction shown in Figs. 7 to 13 the series of supporting members or shelves 16 may be returned to and locked in article supporting position, either before or after the traveller 32a is released for returning the same to its initial position. Upon rotation of the shaft 130, the cams 125 and 129 assume the positions shown in Fig. 10 to cause respectively the release of the dog 121 and the withdrawal of the lower portions 116 out of engagement with the ratchets 34a and 35a. Thereupon the traveller 32a drops by gravity, the dog 121 riding over the latches in the locked position thereof. In the construction of Figs. 7 to 13 the control means for resetting the traveller 32a is separate from the fixed ratchet members 34a and 35a, which renders the structure more efficient mechanically and in operation.

In my invention the superimposed shelves or supports, for the articles to be vended in each compartment or magazine are individually under the control of latching means capable of being readily tripped to release said support and of being automatically engaged to lock the support when the latter is returned to its article supporting position, and the several latching means may be successively tripped by the step-by-step movement of a traveller capable of being advanced with dispatch by the repeated operations of a selected actuating means.

Further, my said invention includes means for rendering the actuator inoperative when the uppermost support is released and the last article in the compartment dispensed, and means for effecting the release of the traveller for returning the same to its initial position, either before or after said latches have been returned to locking positions after being tripped.

Having thus described my invention what I claim and desire to secure by Letters Patent is:

1. Apparatus of the character described comprising a magazine structure, a series of vertically spaced, article supporting members having pivotal portions at one side thereof supported by said structure and being disposed in the magazine thereof, said pivotal portions at one end of the supporting members having vertically directed supporting portions, latch members pivoted centrally thereof upon said supporting portions in offset relation to the pivotal axis of said supporting members, co-operating members upon the structure adapted to be engaged by said latch members at corresponding sides of the pivots thereof for locking said supporting members in position, springs connecting said latch members at opposite sides of the pivots thereof with said

supporting portions for maintaining said latch members engaged with said co-operating members, and means movable transversely of said pivoted latch members for tripping the same to successively release said supporting members.

5 2. In apparatus of the character described, in combination, a magazine structure; a series of vertically spaced article supporting members having pivotal portions at one side thereof supported 10 by said structure and being disposed within the magazine thereof, said pivotal portions at one end of the supporting members having vertically directed supporting portions, latch members pivoted centrally thereof upon said supporting portions 15 towards the ends thereof and having notches in the upper edges of the latch members at corresponding sides of the pivots thereof; co-operating members upon the structure adapted to be engaged by said notched portions for locking 20 said supporting members in position; springs connecting the latch members at the opposite sides of the pivots thereof with said supporting portions below said pivots and being tensioned in the locking positions of said latch members to 25 maintain said notches engaged with said cooperating members, said cooperating members being co-ordinated to interlock automatically upon the return movement of the supporting members to normal position; and means for successively actuating 30 said latch members for disengaging said notches to effect successive release of said supporting members.

3. In apparatus of the character described, in combination, a magazine structure; a series of vertically spaced article supporting members pivoted at one side thereof on said structure within the magazine; spaced latches pivoted upon said structure and co-operating with said members for retaining said members in article supporting position; rotatable guiding members having ratchet teeth thereon in position normally facing each other and in spaced relation corresponding to the latch spacings and having flats extending longitudinally thereof in position to face each other upon rotation of said guiding member, one 40 of said guiding members being mounted for reciprocation, the other guiding member being supported by the structure; a traveling member slidably mounted on said guiding members and having pawls co-operating with said teeth, said traveling member having means engageable with said latches to release said supporting members; means for reciprocating that guiding member arranged to be reciprocated, and means for simultaneously rotating said guiding members for placing 45 said flats in opposing relation and for disengaging the pawls from the teeth to release said traveling member and to allow the return thereof to initial position.

4. In apparatus of the character described, in combination, a magazine structure; a series of vertically spaced article supporting members movably mounted on the structure within the magazine thereof; a corresponding series of latching means mounted on the structure for retaining 50 said members in article supporting position; a traveling member mounted on the structure and arranged to unlock said latching means as

said last named member advances; means arranged to advance said traveling member step by step and to prevent retrograde movement of said member; means supported by said structure arranged to guide said traveling member in association with said series of latching means; means for actuating said second named means; and means arranged to release said traveling member including a vertically extending actuating member rotatably mounted on said structure 5 and carrying detents arranged to prevent retrograde movement of said traveling member only when said actuating member is rotated within a certain range of angular position axially.

5. In apparatus of the character described, in combination, a magazine structure; a series of vertically spaced article supporting members movably mounted on the structure within the magazine thereof; a corresponding series of latches mounted on said structure and arranged 10 to retain said members in article supporting position; a traveling member mounted on the structure having means arranged to trip said latches, said means being pivotally mounted thereon to ride freely over the latches upon the 15 return of the traveling member; means arranged to advance said traveling member step by step; elements on the structure and on the traveling member normally having a locking engagement 20 with each other; means on the traveling member to retain said members in article supporting position for tripping said latches; means thereon for disengaging said elements; and means arranged to actuate both last named means for 25 releasing said traveling member for return over said latches to starting position and for retracting said first named means.

6. In apparatus of the character described, in combination, a magazine structure; a series of vertically spaced article supporting members 40 movably mounted on the structure within the magazine thereof; a corresponding series of latches mounted on said structure and arranged to retain said members in article supporting position; a traveling member on the structure having means arranged to trip said latches, said means being pivotally mounted thereon to ride freely over the latches upon the return of the traveling member; means arranged to advance vertically 45 said member step by step with spaced relationship to said latches, and to prevent retrograde movement thereof, including longitudinally extending elements on the structure and spring controlled elements pivoted on said traveling member and normally retained in engagement with said longitudinally extending elements; means for reciprocating one of said longitudinally extending elements; a cam on said traveling member for releasably retaining said first named means in operative position; a cam on 50 said traveling member between said pivoted elements movable to cam the disengagement thereof from the other elements; and means for actuating said cams including a rotatable member on said structure passing through said cams and keyed thereto for sliding movement of the 55 traveling member thereon.

GEORGE P. MERGENS.
